UNITED STATES PATENT OFFICE.

WILLIAM WILKIE, OF DENNISTOUN, GLASGOW, SCOTLAND.

MACHINE FOR TURNING DOWN THE EDGES OF CLOTH OF WEARING-APPAREL IN THE PROCESS OF MANUFACTURE.

1,230,636.

Specification of Letters Patent. Patented June 19, 1917.

Application filed April 14, 1917. Serial No. 162,206.

To all whom it may concern:

Be it known that I, WILLIAM WILKIE, of 34 Garthland drive, Dennistoun, Glasgow, Scotland, engineer, have invented certain new and useful Improvements in Machines for Turning Down the Edges of Cloth of Wearing-Apparel in the Process of Manufacture, of which the following is a specification.

- 10 This invention which relates to machines for turning over and pressing down the edges of cloth of wearing apparel in the process of manufacture, has for its object to enlarge their scope by acting upon the 15 rear and side portions of the cloth under treatment at one operation, increase their efficiency, vary their application and adaptation to the many parts of a garment or wearing apparel under treatment so that 20 not only cuffs, collars and pockets and similar rectangular pieces which have hitherto been treated in machines for folding blanks of aforesaid parts, but circular, oval and elliptical portions of cloth may be treated 25 with similar good results. The invention consists of a machine of ordinary table height supported on legs, and upon the surface of the table, part of the mechanism is actuated and mounted. The two outer laterally movable infolders are invested with 30 a backward and forward movement, and with a long reciprocating infolder lying longitudinally across the machine, are designed to crease the side and rear edges of 35 the cloth, the outer lateral infolders having also a transverse movement, and being carried by blocks on a horizontal rod or bar mounted on a slidable element which is moved by a pair of eccentrics or cams joined 40 together by a long connecting rod. A hand lever is used to turn the eccentrics or cams and is mounted on one of the eccentrics or cams. One or two central detachable dies which coöperate with the infolders previously mentioned are mounted on a hinged 45 lever which is capable of being raised and swung back at will in order to insert into the machine the pieces of cloth to be treated. That part of the table adapted to receive
- the cloth to be acted upon has its surface 50 movable from beneath in order to exert pressure from beneath which is obtained by a treadle acting upon a ram or plunger. Heat is also applied. As with this class of machine, the rear and lateral infolders are 55 brought into contact with the inner die or dies which are stationary during the creasing operation with the plates of the one overlapping the plates of the other and with the edges of the cloth interposed and acted 60 upon between them.
- In order that my invention may be properly understood and readily carried into effect, I have hereunto appended one sheet of drawings, of which 65
- Figure 1 is a plan of the machine embodying my invention.
- Fig. 2 is a front view, and
- Fig. 3 is a cross section of the same taken on the line *a, b*, Fig. 1. 70
- Fig. 4 is a section of part of the blocks and dies with the cloth interposed therebetween.
- Fig. 5 is a perspective view of the same with the dies and blocks separated from 75 each other, Fig. 6 is an alternative device for moving the reciprocating part of the machine, all hereafter more fully referred to and described.
- Referring to the drawings, A is the table. 80 A¹ is the divided portion thereof adapted to be heated and is designed to rise and fall by virtue of the forked arm A³ when operated by the treadle A². B is the reciprocating or slidable infolder part mounted on said table. C, D, are two eccentric disks mounted on the surface of the table at C¹, D¹, and connected by the connecting rod D² and operated by the hand lever D³ for moving the said slidable part backward and forward within the guide pieces E, F. B² are slots in which the pins B³ fixed to the steel knife-edge plates X¹, X² may be adjusted and fixed with thumb screws. G, H are the infolders for carrying the infolder plates, 85 and which infolders are carried upon the horizontal rod or bar I which rod or bar I is fixed to the said reciprocating infolder 90
- 95

part B. The infolders G, H, while free to oscillate are kept from rising and made to resist the pressure of the raisable table A¹ by the extended bent in portions G¹, H¹, in the turning down and pressing operation. In this connection it will be seen that parts G¹ and H¹ carry screws which are adjustable beneath the lower edge of a flange depending from the table A. However, it will be understood that these screws are not set up tight against the edge of the flange, since to do so would prevent the infolders from moving, but are merely set up close enough to prevent B from lifting when the ram A is forced up. These outer blocks carry the thin steel infolder plates X¹. The dies P and Q are adjustably attachable to and detachable from depending plates T, U, by means of thumb screws, and by thumb screws P¹, Q¹ in open slots P², Q² they adjustably support steel plates forming the central die or dies. This arrangement permits of various forms of dies being used. The said blocks G and H with the said knife edge plates X¹ are adapted to move laterally in conjunction with the movement of the reciprocating part B due to the attachment of links K, L, pivoted to the blocks M and N which are carried on the horizontal rod or bar J mounted on the fixed part of the table and can be clamped thereto at any given point by means of the set screws M¹ and N¹. The lever O is hinged at O¹ and is capable of being raised, and being locked in that position by the coaction of the levers O² and O³ Fig. 3. Said lever carries the two central or inner dies or templets P, Q, and is provided with two arms R, S, pivoted at one end to the plates T, U, and the other end to a plate J¹, which plate J¹ is adjustably connected to the hinged lever O; the plate W slides along the said hinged lever O and carries the rod V to which are attached the plates T, U, supporting the dies P and Q provided with knife edges or thin steel die plates X, and these, in conjunction with the outer infolders and the longitudinal infolder B having a knife edge or rear die B¹ are employed in the turning over and pressing down of the cloth and are actuated by hand, but in themselves do not essentially constitute the novel elements. It will be seen that the plate J¹ can be adjustably moved along the lever O to adjust the central dies and fixed in position by the clamping screw J². It will also be seen that a considerable lateral movement to and from the center of the machine is imparted to the dies due to the radiating of the arms R, S, and by fixing the plate J¹ and moving the plate W forward, this movement may be utilized for freeing the central dies from the creased edges before pressing the creases in cases where it is nec-

essary to move the central dies inward on account of the shape of the cloth treated. When possible however, the central dies are freed from the creased edges by freeing the plate J¹ and moving it and the plate W forward. It will be observed that both the side and back portions of the cloth are operated simultaneously by a handle from the eccentric D operating the longitudinal plate.

It will be seen that when the handle D³ is turned to operate the eccentrics C and D, the part B is constrained by the guides E and F to move in a path parallel to the central lever O and hence perpendicular to the fixed rod J, and the movement of B causes the lateral movement of G and H, but the movement of G and H is perpendicular to that of B owing to the fact that the inclined arms K and L are fixed to the bar J and the latter is fixed to the table A. Also, the infolders G and H move in opposite directions owing to the opposite inclinations of arms K and L, the infolders both moving outwardly or inwardly at a given time.

It is to be explained that any suitable shape of infolder plates may be fitted on to the infolders G, H, and the infolder plate B, and the dies P and Q. The infolders G and H are moved together by the links K and L which are fixed to the adjustable blocks M and N and the dies P and Q are moved when required by the arms R, and S, pivoted to the adjustable plate J¹, and the plate W is capable of being moved along the hinged lever O to and from the plate J¹ for adjusting the central dies, and the screw W¹ is used to give the various adjustments when the knife edges B¹ and X¹ of the infolder B and infolders G and H are made to overlap with coöperating edges as is common to other analogous machines, the die plates X of the dies P and Q with the cloth interposed between them and the edges X¹ being shown in detail in Fig. 4 in order to illustrate the manner in which the cloth is folded.

Referring to Fig. 6, the mechanism for moving the reciprocating part of the machine consists of a quadrant and rack 2, the quadrant 1 being moved by a hand lever 3 mounted at one side of machine which communicates motion to the reciprocating part of the machine by the medium of a rack.

Claims:

1. In a machine of the class described in combination, a table, a slidable element movable on the surface of said table, outer infolders having knife-edges and actuated by said movable element, a bar or rod fixed relatively to said table, blocks adjustable along said bar or rod, and links or arms connecting said bar to said infolders.

2. In a machine of the class described in combination, outer lateral infolders, a pair

of oppositely inclined arms pivoted at one end, central dies or templets attached to the non-pivoted ends of said arms, and means whereby said central dies or templets may be moved apart toward said infolders or together as desired, said means comprising a central lever and a rod extending at right angles to said lever, said rod being slidably

mounted on said lever and said dies being slidably mounted on said rod. 10

In witness whereof I affix my signature in presence of two witnesses.

WILLIAM WILKIE.
